UNITED STATES PATENT OFFICE

SOTOO YOSHIMURA, OF SHANGHAI, CHINA

DUPLICATING RIBBON MECHANISM

Application filed September 11, 1925, Serial No. 55,841, and in Japan September 11, 1924.

This invention relates to a copying apparatus for typewriters, and more particularly to a machine for typing letters successively in duplicate, comprising an arrangement 5 provided with copying ribbon reels and a copying ribbon guide to permit the copying ribbon to pass between the paper sheets.

The invention further comprises a device for moving the ribbon automatically along a 10 typewriting line by rolling up the copying ribbon.

In order to typewrite any papers in duplicate simultaneously in a typewriter carbon paper, inserted between duplicate papers, 15 has heretofore been employed, the said carbon paper being inserted between the papers each time the papers are changed. Therefore, when typewriting many papers in duplicate successively, it is inconvenient to re-

20 insert the carbon paper or a special copying ribbon and to change the papers. The present invention is intended to avoid such inconveniences and its objects are as follows:—

(1) To provide a duplicating ribbon which 25 may be inserted between and moved transversely of the papers;

(2) To provide means for moving the duplicating ribbon simultaneously with the rotation of the platen;

30 (3) To space the ribbon from the paper to prevent contact between the ribbon and paper.

In the accompanying drawings, Fig. 1 is a perspective view of the copying ribbon guide, 35 Fig. 2 is a perspective view showing the mounting for the copying ribbon and means for inserting the paper, and Fig. 3 is a perspective view showing the support for the paper rolls and the arrangement for rolling 40 up the copying ribbon.

The metallic ribbon guide shown in Fig. 1 is arcuate in cross section and has a long slit through which the ribbon passes. The portions adjacent the ends are wrapped with 45 sheet metal (1) and are thicker than the remaining portions thereof. Both ends are made concentric with the circumference of the platen and rest against the platen to contact smoothly therewith. In its supported 50 position it rests between the ordinary rib-

bon and the platen and the copying ribbon is so supported, that each time the key is pressed, the type strikes the ordinary and copying ribbons at the same time. One sheet (3) of the papers is passed between the ordinary ribbon and the copying ribbon and the other sheet (4) is passed between the copying ribbon and the platen and thus the duplicate papers can be typewritten simultaneously.

55 In this case the lower side of the copying ribbon is held in the groove (5) at the lower side of the ribbon guide and, since the middle portions of the projecting ends of the ribbon guide are slightly thicker than the other portions, as above described, a clearance is provided to permit the passage of a sheet of paper between the platen and the copying ribbon.

60 To support the ribbon guide in the above described position, the arms (6) (6') which are curved at their ends and extend forwardly to the front of the platen are provided, and into small holes (7) suitably located in the arms, projections (8) (8') on 65 the ends of the ribbon guide (Fig. 1 and Fig. 2) are inserted and fixed. In order to wind the copying ribbon on one ribbon reel gradually worm wheels 9 are mounted on both of the extended ends of the platen shaft or axle. Gear wheels (10) on the two shafts (11) are 70 geared to the worm wheel to rotate the ribbon reels (12) (12') on which the ribbon is wound (Fig. 2, Fig. 3). The ribbon reel 12 is mounted freely on one of the said shafts but, if 75 desired, may be secured by means of a pin (13) and thus the copying ribbon is arranged to be moved to the right or left (Fig. 2, Fig. 3).

80 In case it is necessary to change the direction of movement of the copying ribbon several times owing to the form of the typewriter, thin steel guides (14) are used (Fig. 2). The original and duplicate papers (3) 85 and (4) are respectively inserted as usual to travel forwardly from the back of and underneath the platen and between the platen and a pressure roller which presses the platen 90 from underneath and rotates freely. These 95 100

papers are fed from rolls (3') (4') respectively (Fig. 2, Fig. 3).

Shafts (15) (15') pass through the rolls (3') (4') and the ends of the said shafts are inserted into grooves (17) (17') (17'') (17''') provided in the rear of the support (16), (Fig. 1). The shafts and the grooves are respectively of such size that the shafts can rotate freely in the said grooves. Then, 10 as the papers are inserted between the platen and the pressure roller which presses the platen from underneath the papers are drawn forwardly with the rotation of the platen. The support 16 is arranged so as to move to 15 the right and left by means of wheels (18) (18') fixed thereto and riding on a rail (19) secured in the rear of the typewriter. To the said support, arms (20) are connected at each end of the carriage, the said arms moving with the carriage. In this case in order 20 to facilitate movement toward the left, the rail is slightly inclined towards the right end. Therefore, in order to connect the arms to the support, links (21) are arranged so as to allow 25 the support to move vertically. The inclination of the rail aids the force of the spring, which pulls the carriage and thus even comparatively heavy rolled papers can move together with the carriage without any 30 difficulty.

When typewriting of one document has been made, the rolled paper may be cut off. For this purpose a cutting apparatus (22) made of steel, mounted on the arms (6) (6') 35 which support the ribbon holder is provided, and the paper can be cut off at any time by being pulled forward.

It is believed in view of the foregoing description that a further detailed description 40 of the invention is unnecessary. Likewise it is believed that the advantages of the invention will be readily apparent.

Having thus fully described the invention what is new and desired to be secured by Letters Patent is:—

A typewriting mechanism of the class comprising in combination, a typewriter carriage, a platen having an extension axle, a ribbon guide, said guide being arcuate in the cross 50 section and formed to rest concentrically with respect to said platen and extending along the printing line of the platen, means to direct the ribbon along this line, a pair of arms on the typewriter frame for supporting said 55 guide, means on said guide for detachably securing said guide to said arms, spacing means on said guide to space the ribbon from said platen, ribbon reels and means to drive said reels comprising duplicate sets of worm 60 gears attached at each end of the extension axle of the platen.

In testimony whereof I hereto affix my signature.

S. YOSHIMURA.
